UNITED STATES PATENT OFFICE.

JOSEPH JEROME EAGAN, OF NEW CASTLE, PENNSYLVANIA.

COLLAR.

Application filed December 8, 1921. Serial No. 520,947.

To all whom it may concern:

Be it known that I, JOSEPH JEROME EAGAN, a citizen of the United States, and a resident of New Castle, in the county of Lawrence and State of Pennsylvania, have invented certain new and useful Improvements in Collars, of which the following is a specification.

This invention relates to improvements in collars used as wearing apparel.

The object of the invention is to provide a collar of the so called turned down type with a novel form of button hole in one tab thereof, adapted to facilitate the buttoning 15 of the collar about a person's neck and properly adjusting the same after being buttoned.

Also an object of the invention is that the button hole be adapted to permit locking the associated collar button in adjusted position.

20 The invention is illustrated by way of example in the accompanying drawings, in which:—

Figure 1 is a perspective view of a collar showing the tabs thereof connected by a collar button and the under tab formed with button hole of the present invention.

25 Figure 2 is a front elevation showing the end portions of the collar and associated tabs and more clearly illustrating the invention,

30 Figure 3 is a fragmentary front elevation showing the ends of a collar connected or held together by a collar button and particularly illustrating how the collar button is locked against movement.

Referring to the drawings more particularly, C indicates generally a collar of the type heretofore referred to and consisting in a neck band portion 10, the turned down portion 11 and the two flap portions 12 and 13 in which the respective ends of the neck band 10 terminate. The flap 12 may be referred to as the under flap or the shorter flap, while the flap 13 may be referred to as the upper flap or the longer flap. The band 10 is provided with the usual rear button hole as at 14, and the flap 13 is provided with the usual slit or button hole 15.

35 The present invention consists in providing the shorter or under flap 12 with a singular shaped button hole to obtain the advantages mentioned in positioning a collar about a person's neck. The button hole comprises an inclined portion 16 which terminates at its lower end in the portion 17. The portion 16 is relatively broader than the

portion 17 as shown, and the portion 17 of the button hole is disclosed at substantially right angles to the portion 16. This however is optional as the portion 17 does not need to be exactly at right angles to the portion 16.

In positioning the collar about a person's neck the rear button is first extended through the button hole 14 then the button hole of the shorter flap 12 has extended therethrough the front collar button as at 17', and the button 17' is preferably extended through the upper end of the portion 16 in the button hole of the flap 12. As is obvious by such an arrangement no great effort need to be exerted in buttoning the flap 12, in that by extending the button through the upper end of the associated button hole the collar is slightly increased in length. The tab 13 may now be brought over and buttoned to the collar button 17' and then extended beneath the turned down portion 11. The upper end of tab 12 may now be grasped and pulled upward so that the collar button 17' may slide downwardly and then into the portion 17 of the button hole and thus locking the tab in position.

It also should be observed that the purpose of making the portion 16 of the button hole 85 of the tab 12 larger than the angular portion 17 is to facilitate the upward and downward movement of the collar button therein.

I claim.

1. A collar of the character described 90 having a tab or extension at each end, one of said tabs being shorter than the other, and the shorter tab provided with a button hole consisting in an inclined slot, the upper end of which is nearer to the free end of 95 tab than the lower end thereof.

2. A collar of the character described having a tab or extension at each end, one of 100 said tabs being shorter than the other, and the shorter tab provided with a button hole consisting in an inclined slot, the upper end of which is nearer to the free end of tab than the lower end thereof, and the lower end of the slot terminating in a second slot disposed at an angle to the inclined slot.

3. A collar of the character described having a tab or extension at each end, one of 110 said tabs being shorter than the other, and the shorter tab provided with a button hole consisting in an inclined slot, the upper end of which is nearer to the free end of the tab than the lower end thereof, and the lower

end of the slot terminating in a second slot extending laterally and forwardly with relation to the first named slot.

4. A collar of the character described having a tab or extension at each end, one of said tabs being shorter than the other, and the shorter tab provided with a button hole consisting in an inclined slot, the upper end

of which is nearer to the free end of tab than the lower end thereof, the lower end of the slot terminating in a second slot extending laterally and forwardly with relation to the first named slot, and said second named slot being of less width than the first named slot.

JOSEPH JEROME EAGAN.
